UNITED STATES PATENT OFFICE.

ADOLPHE PAROUTAUD, OF NEW YORK, N. Y.

DESIGN FOR A VESSEL FOR TABLE USE.

No. 38,505.

Specification for Design.

Patented April 2, 1907.

Application filed February 19, 1907. Serial No. 358,328. Term of patent 7 years.

To all whom it may concern:

Be it known that I, ADOLPHE PAROUTAUD, a citizen of the United States, and a resident of the city of New York, borough of Manhattan, in the county and State of New York, have invented a new, original, and ornamental Design for a Vessel for Table Use, reference being had to the accompanying drawing, in which the figure is a perspective view of a vessel for table use, showing my design.

I claim—

The ornamental design for a vessel for table use as shown.

ADOLPHE PAROUTAUD.
